UNITED STATES PATENT OFFICE.

EDWARD B. JAMES, OF CORDELE, GEORGIA.

PLOW.

1,110,290.

Specification of Letters Patent.

Patented Sept. 8, 1914.

Application filed September 12, 1911. Serial No. 648,918.

To all whom it may concern:

Be it known that I, EDWARD B. JAMES, a citizen of the United States, residing at Cordele, in the county of Crisp and State of Georgia, have invented a new and useful Plow, of which the following is a specification.

This invention relates to plows, and has for its object to provide a novel frog and adjustable connection of the standard of the

10 frog with the plow beam.

With the above object in view this invention is embodied in the novel construction and arrangement of parts as hereinafter described and as illustrated in the accompanying drawings, wherein similar reference characters indicate similar parts, and wherein,

Figure 1 is a perspective view of a plow 20 constructed in accordance with the invention, with parts broken away and parts shown in dotted line. Fig. 2 is an elevation of the frog. Fig. 3 is a perspective view of a detail. Fig. 4 is a section taken through the 25 upper end of the standard, illustrating the means for adjusting the plow beam. Fig. 5 is a front view of a modified form of frog.

Referring specifically to the drawing, the frog comprises the shoe 13 and the pallet or 30 resting plate 14, and has an integral standard 6. The forward side of the standard is gently curved forwardly with its upper end overhanging the tip or point of the frog.

The lower portion of the standard is solid 35 and merges into the corner of the frog, while the upper portion of the standard is enlarged and is U-shaped in cross section with the opening disclosed rearwardly so as to provide cheeks 7. The cheeks 7 are widened 40 and have arcuate slots 17 adjacent their upper ends. A handle engaging member 11 projects upwardly in an inclined position from the rear end of the shoe 13, and is connected to the solid or lower portion of the 45 standard by the integral portion 12. The handles 20 are attached to the portion 11 by bolts or other securing members, it being noted that in this manner, the handles are rigidly connected to the standard as well as 50 to the frog proper.

The plow beam which has been denoted by the numeral 5, is constructed of an I-beam, the rear portion of the beam being curved downwardly gently on an arc corresponding 55 with the arc of the standard. The rear end of the standard is snugly housed between the

cheeks 7 of the standard, the flanges of the beam contacting with the cheeks. The bolt 10 passes through the lower ends of the cheeks and through the web of the beam so 60 as to fulcrum the beam and standard together, and a bolt 9 passes loosely through the slots 17 and through the web of the beam, to clamp the cheeks against the flanges of the beam. In order to lock the bolt 9 in 65 position, after it has been tightened, an elongated washer 8 has been mounted on each end of the bolt. One of the cheeks has a series of small circular indentures or notches 18 in its outer side beyond each end of the 70 slot 17, and the corresponding washer is provided with a small circular spur 16 adjacent one end, this washer being rotatable on the bolt when the bolt is loosened so that the spur may be engaged with either series of 75 indentures according to the adjustment of the standard and beam relative to each other. It will be noted that the washers 8 bear against the outer sides of the cheeks, the adjoining faces of the cheeks and washers being flat or smooth with the exception of the indentures or notches as above indicated. The washers also cover the slots, as 80 is desirable.

With this construction and combination of 85 parts as above described, it will be noted that a desirable, simple, compact and efficient plow structure is provided, and one which permits of the ready and effective adjustment of the frog and beam relative to 90 each other. To adjust a frog and beam relative to each other, the bolt 9 is loosened, to relieve the cheeks from the flanges of the beam, and to loosen the washers from the cheeks, the spur being disengaged from the 95 corresponding indenture or notch. After the standard and beam have been properly adjusted or swung relative to each other, they may be so locked by first swinging the proper washer 8 in one position or the other 100 so that the spur may engage the proper series of indentures 18, and then tightening the bolt 9 so as to first clamp the washers against the cheeks and then to clamp the 105 cheeks against the beam. The washers in being clamped against the cheeks will cause the spur to be locked in engagement with the respective indenture, and as a result, the bolt 8 and the beam 5 will be locked in position relative to the standard.

Attention is directed to the fact that the 110 distance between the bolt 9 and the spur 16

is less than half the distance between the two series of indentures 18, whereby when the washer 8 having the spur 16, is rotated to permit the spur to engage the respective series of indentures, a relatively large amount of adjustment between the beam and frog may be had. Thus, when the spur 16 is engaged in one series of indentures 18, as seen in Fig. 4, the frog will be swung downwardly and rearwardly, while when the spur 16 is engaged in the other or forward series of indentures 18, the frog will be swung forwardly and upwardly slightly.

In the form shown in Fig. 5 the frog is provided with a pair of pallets 19 on the respective sides thereof, this construction of frog being adapted for the middle burster or lister type of plow. The standard 6 is identical with the standard of the former frog, whereby the frogs may be made interchangeable with the plow beam to adapt the same for either the middle burster plow or a turn plow.

What is claimed is:—

25 In a plow, a frog provided with a standard of U-shaped cross section, a plow beam

having its rear end curved downwardly and pivoted between the sides of the standard, the sides of the standard having arcuate slots therein curved about the pivotal point 30 of the beam, a bolt carried by the beam and passing through the said slots, the faces of the sides of the standards being smooth with the exception of a series of small outer indentures beyond each end of one of the said 35 slots, and elongated washers mounted upon the ends of the bolt over the said slots, one washer having a single small circular spur adjacent one end thereof the distance between the bolt and spur being less than half 40 the distance between the two series of indentures, and the said washer being rotatable when the bolt is loosened, in order that the spur may engage either series of indentures.

In testimony that I claim the foregoing as 45 my own, I have hereto affixed my singature in the presence of two witnesses.

EDWARD B. JAMES.
